CLAIM

The ornamental design for a handset, as shown and described.

DESCRIPTION

FIG. 1 is a front perspective view of a handset showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing the environmental structures in the FIGS. 1-7 are for illustrative purposes only and form no part of the claimed design. The depicted contrast in shading represents a change in color, material, or surface texture.

1 Claim, 4 Drawing Sheets
